UNITED STATES PATENT OFFICE.

SEWELL POWIS AMBROSE, OF VANCOUVER, BRITISH COLUMBIA, CANADA.

AMUSEMENT DEVICE.

Application filed October 4, 1927. Serial No. 224,006.

My invention relates to improvements in amusement devices the objects of which are to provide means whereby two persons may derive healthful exercise and enjoyment at 5 the same time. The invention consists essentially of a seesaw which is adapted to rotate about a vertical axis when being moved up and down, and having means operable by the users for imparting movement to the 10 seesaw, as will be more fully shown in the accompanying drawings and described in the following specification, in which:—

Fig. 1 is a general view of the invention.

Fig. 2 is an enlarged sectional view of the 15 base mechanism.

Fig. 3 is a side view of one of the track wheel hangers.

Fig. 4 is a view of an operating lever.

Fig. 5 is an enlarged sectional view of a 20 modified base mechanism.

In the drawings like characters of reference indicate corresponding parts in each figure.

The numeral 1 indicates generally a base 25 consisting of a pedestal 2 surrounded by an undulating concentric track 3, the purpose of which will hereinafter appear. A recess 4 is formed concentrically in the upper face of the pedestal 2 which is adapted to receive 30 the shaft 5 of a rotary standard 6, the upper end of which is adapted to be pivotally connected to a bed plate 7 by a pin 8.

A cross arm 9 extends transversely of the 35 rotary standard 6 which is drilled to form a journal for a shaft 10. The shaft 10 extends beyond the ends of its journal and is fitted adjacent one end with a bevelled pinion 11 having a key 12 or other suitable fastening means and adjacent the opposite 40 end with a similar pinion 13, which however is freely rotatable upon the shaft. The pinions 11 and 13 mesh with a bevelled ring 14 mounted upon or formed integrally with the pedestal 2. To the opposite ends of the 45 shaft 10 are secured a pair of cranks 15 having crank pins 16 and which are preferably set at a right angle to each other.

Mounted upon the bed plate 7 is a plank 50 or seesaw 17 which is provided with a pair of track wheel hangers 18 so spaced as to be directly over opposite portions of the track 3. The track wheel hangers are preferably formed with a plate 19, see Figure 3, having downwardly projecting lugs 20 at opposite 55 ends, which are apertured for the purpose of receiving a pivot pin 21. Upon this pin a

substantially U-shaped member 22 is mounted, the extremities of which extend so close to the plate 19 at 23 as to permit of a very slight pivotal movement only of the U-shaped member. Mounted at the base of the member 22 is a wheel 24 which travels upon the track 3, thus imparting a vertical reciprocating motion to each end of the plank 17.

Adjacent each end of the plank 17 an operating lever generally indicated by the numeral 25 is pivotally mounted, see Figure 4, which lever is formed preferably of a pair of side members 26 pivotally connected to the side edges of the plank as at 27 and connected together by an upper horizontal rod 28 forming a hand grip and a lower horizontal rod 29 forming a treadle. Pivotally connecting one of the side members 26 of 75 each operating lever 25 to one of the cranks 15 is a connecting rod 30.

In the modified form of base mechanism a ball socket 31 is disposed concentrically within the undulating track 3 and rockingly mounted in the socket is a standard 32 having a spider 33 consisting of one rotatable shaft 34 and other non-rotating shafts 35, on the ends of which rollers 36 are mounted, one roller on the rotatable shaft being secured thereto so that as the shaft is rotated, traction is obtained between said roller and the track to cause the standard 32 to rotate. Transversely of the standard and in parallel relation to the rotatable shaft 34 is a bearing 37 in which a further shaft 38 is journaled, having cranks 39 at opposite ends, and keyed to said shaft is a pinion 40 which meshes with a gear 41 keyed upon the shaft 34 so that rotation of the cranks 39 will impart rotation through the pinion 40 and the gear 41 to the shaft 34 in an opposite direction. A plank 17 is secured to the head of the standard 32, which is provided with operating levers and connecting rods having operating connection with the cranks 39 as shown in Figure 1.

Having thus described the several parts of my invention I will now briefly explain its operation.

Two persons assume a seated position at opposite ends of the plank 17 and face each other, they then place their feet upon the respective treadles 29 of the levers 25 and grip the respective hand grips 28. On reciprocal movement being imparted to

the levers by the persons seated upon the seesaw, a reciprocatory and rotary motion is imparted thereto through the connecting rods, the drive ring and their associated 5 parts.

What I claim as my invention is:

1. An amusement device comprising a base, having a concentric gear ring, a standard upon the base pivotally supporting a 10 seesaw, a shaft carried by the standard having a pinion in mesh with said gear ring, and means operable by one of the users for imparting rotation to the shaft and to cause the pinion to travel about the ring whereby 15 rotation is imparted to the seesaw.
2. An amusement device comprising a base, having a concentric gear ring, a standard upon the base pivotally supporting a seesaw, a shaft carried by the standard having a pinion in mesh with said gear ring, and means operable by one of the users for 20 imparting rotation to the shaft and to cause the pinion to travel about the ring whereby

rotation is imparted to the seesaw, and means as the seesaw is rotated about the 25 base for imparting reciprocation to the seesaw.

3. An amusement device comprising a base, a seesaw, a standard upon the base pivotally supporting said seesaw, a horizontally disposed gear ring carried by the base and surrounding the standard in concentric relation thereto, a transversely extending shaft carried by the standard and equipped with a pinion meshing with said gear ring, means operable by an occupant of the seesaw for imparting rotation to said shaft to cause the pinion to travel upon the gear ring, a circular undulating track carried by the base, and wheel elements carried by the seesaw and arranged to travel along the undulating surfaces of the track during rotation of the seesaw.

Dated at Vancouver, B. C., this 23rd day of September, 1927.

SEWELL POWIS AMBROSE.
